[57] **CLAIM**

The ornamental design for a ball tossing device, as shown and described.

DESCRIPTION

FIGS. 1 is a top plan view of the ball tossing device showing my new design;

FIGS. 2, 3 and 4 are right side, back, and front views, respectively, thereof;

FIG. 5 is a cross-sectional view thereof taken at the line 5 — 5 of FIG. 1;

FIG. 6 is a cross-sectional view thereof taken at the line 6 — 6 of FIG. 1;

FIG. 7 is a cross-sectional view thereof taken at the arcuate line 7 — 7 of FIG. 1;

FIGS. 8, 9, 10 and 11 are views corresponding to those of FIGS. 1, 2, 3 and 4, respectively, showing a modified form of the ball tossing device;

FIG. 12 is a cross-sectional view of the modified form of the design taken at the line 12 — 12 of FIG. 8;

FIG. 13 is a cross-sectional view thereof taken at the lines 13 — 13 of FIG. 8; and

FIG. 14 is a cross-sectional view thereof taken at the line 14 — 14 of FIG. 8.

Fig. 3.
